ELECTRIC IRON

Edward A. Farr, Columbus, Ind., assignor to
 Noblitt-Sparks Industries, Inc., Columbus, Ind.,
 a corporation of Indiana

Application June 10, 1944, Serial No. 539,667

5 Claims. (CL 219—25)

1

My invention relates to electric sad-irons, and has for its primary object the production of an iron in which the cord supplying current to the heating element may be made to extend laterally alternatively in either direction from the iron. Another object of my invention is to provide a simple and effective means for securing the cord to the iron in a way such that tension in the cord will not be transmitted to the connection between the cord-wires and the terminals to which they are connected.

In carrying out my invention, I provide the iron with a handle of generally conventional form. The rear portion of this handle is provided with a downwardly opening recess in the rear and side walls of which there is a continuous slot. A generally U-shaped closure is removably associated with this slot, and such closure is relieved at one end to provide a space for the passage of the cord. The closure is reversible in the slot so that the relieved end may be disposed alternatively at either side of the iron, thus permitting the cord to extend laterally in either direction from the iron.

The accompanying drawings illustrate my invention: Fig. 1 is a fragmental side elevation of the rear portion of an electric sad iron; Fig. 2 is a view similar to Fig. 1 but with portions of the handle broken away; Figs. 3 and 4 are respectively a rear elevation and a fragmental plan view of the iron; Fig. 5 is a section on the line 5—5 of Fig. 2; and Fig. 6 is a section on the line 6—6 of Fig. 2.

The iron illustrated in the drawing comprises a body portion 10 including a sole-plate 11 and any desired form of means (not shown) for heating such sole plate. My invention is not concerned with the heating means or other elements in the body of the iron. To the iron there is affixed a handle having a generally upright rear portion 13 and a grip 14 extending forwardly from such rear portion.

The rear portion 13 of the iron is provided with a relatively large downwardly opening recess 15. In the rear wall of this recess there is provided a slot 16 which extends across the back of the rear portion 13 and continuously forward therefrom along the sides of such rear portion. The slot 16 is symmetrical about the median plane of the handle. Associated with the slot 16 I provide a closure 18 having a rear leg 19 and two side legs 20 and 21, the latter serving to close those portions of the slot 16 which extend forwardly along the sides of the rear portion 13 of the handle. Desirably, the outer edges of the

2

slot 16 are provided with rabbet grooves and the closure 18 with flanges 22 receivable in such grooves, as will be clear from Fig. 6. The exterior of the closure 18 is formed to blend with the exterior lines of the handle.

Except for the fact that one of its legs, here shown as the leg 20, is shorter than the other the closure 18 is symmetrical about the median plane of the handle and conforms to the shape of the slot 16. When the closure is in place in the slot, the latter will therefore be completely closed except for an opening between the end of the short closure-leg 20 and the adjacent end of the slot. Through this opening extends the cord 15 25 by means of which electric current is supplied to the heating element of the iron. Desirably, the ends of the slot 16 and the end of the short closure-leg 20 are semicircular in conformation so that the cord-receiving opening will be substantially circular.

For the purpose of securing the cord 25 to the iron in a way which will prevent tension in the cord from being transmitted to the connection between the cord-wires and terminals of the iron,

25 I provide on the front wall of the recess 15 a vertical rib 27 which terminates short of the lower end of the recess 15. The lower end of the rib 27 is formed with an upwardly extending recess 28 somewhat smaller in width than the diameter of the cord 25. When the cord is forced into the recess 28 it is effectively clamped to the iron-handle so that it cannot move longitudinally of itself relative to such handle. To aid in this clamping action, one of the faces of the 30 groove 28 may be provided with one or more projections 30.

The closure 18 is held in place in the slot 16 by a screw 32 which is located in the median plane of the handle and which passes through 35 the rear closure-leg 19 into the rib 27.

As is customary in cords associated with irons and other electrical appliances, I prefer to provide the cord 25 with a strain-reliever 34 adapted to prevent sharp bends in the cord at the point 40 where it leaves the iron. As will be clear from Fig. 5, the strain-reliever 34 is wound from wire and has a close-wound portion 35 of uniform diameter, a few close-wound turns 36 of larger diameter at one end of the portion 35, and an 45 open-wound portion 37 of gradually increasing diameter at the other end of the portion 35. The slot 16, at least at its end portions, has a width equal to or slightly greater than the diameter of the close-wound portion 35 of the strain 50 reliever; and the inner faces of the closure-leg 21

and of the rear handle-portion 38 are desirably relieved to provide a seat for the enlarged end 36 of the strain reliever.

The ends of the wires of the cord 25 are connected to the terminals of the iron in the iron-body 10, and the cord extends upwardly therefrom into the recess 13, where it is forced by lateral movement into the groove 28, as shown in Figs. 2 and 5. Sufficient slack is left in the cord between the groove 28 and the terminals to which the ends of the cord-wire are connected to permit ready removal of the handle from the iron-body 10. If the iron is to be used by a right-handed person, the closure 18 is disposed in the slot 16 in the position shown in full lines in Fig. 5—i. e., with the short closure-leg 21 at the right of the handle. This permits the strain-reliever 34, through which the cord 25 passes, to be located in the full-line position shown in Fig. 5, and the cord therefore extends laterally to the right from the iron. If the iron is to be used by a left-handed person, the screw 32 is removed and the closure is withdrawn from the slot 16. The cord 25 and strain reliever 34 are then swung to the opposite end of the slot 16 or into the dotted-line position of Fig. 5, following which the closure 18, rotated 180° about the axis of the opening that receives the screw 32, is replaced in the slot and secured by the screw 32.

The enlarged end 36 of the strain reliever 34, having a diameter greater than the width of the slot 16, prevents the strain reliever from being readily removed from association with the handle when the cord is swung from one end of the slot to the other. To facilitate initial entry of the enlarged end 36 of the strain reliever into the slot, the latter may be widened, preferably near its mid-point, as indicated at 40 in Fig. 6.

I claim as my invention:

1. In an electric sad-iron having a body portion provided with an electrical resistance heating element, a handle for said iron having a generally horizontal grip and a generally vertical rear portion between said grip and body, said vertical handle-portion being hollow and provided with an elongated slot extending from one side of the vertical portion to the other across the back of said vertical portion, a flexible cord comprising wires for supplying electric current to said heating element, said cord extending through said slot, a rigid slot-closure disposed in said slot and extending from one end thereof to a point adjacent to but spaced from the other end to provide an opening through which said cord passes, said closure being reversible relative to the slot whereby to provide such cord-passing opening alternatively at either end of the slot and also insertable into and removable from the

slot by rectilinear movement in the plane of the slot, and means for holding said closure in place in the slot in either of its alternative positions.

2. In an electric sad-iron having a body portion provided with an electrical resistance heating element, a handle for said iron having a generally horizontal grip and a generally vertical rear portion between said grip and body, said vertical handle-portion being hollow and provided with an elongated slot extending from one side of the vertical portion to the other, a flexible cord comprising wires for supplying electric current to said heating element, said cord extending through said slot, a rigid slot-closure disposed in said slot and extending from one end thereof to a point adjacent to but spaced from the other end to provide an opening through which said cord extends, said closure being reversible relative to the slot whereby to provide such cord-passing opening alternatively at either end of the slot and also insertable into and removable from the slot by rectilinear movement in the plane of the slot, and means for holding said closure in place in the slot in either of its alternative positions.

3. The invention set forth in claim 2 with the addition of an interior rib on said vertical portion opposite said slot, said rib being provided with a downwardly opening groove tightly receiving said cord.

4. The invention set forth in claim 2 with the addition of an interior rib on said vertical portion opposite said slot, said rib being provided with a groove tightly receiving said cord.

5. The invention set forth in claim 2 with the addition of cord-clamping means located interiorly of said vertical handle-portion and opposite said slot for clamping said cord to said handle.
